US00D788317S

(12) **United States Design Patent** (10) **Patent No.:** **US D788,317 S**
Orcutt (45) **Date of Patent:** **** May 30, 2017**

(54) **DILUTOR CLAW FOR
CHROMATOGRAPHIC EQUIPMENT**

D600,083 S * 9/2009 Kerce D8/28
D778,699 S * 2/2017 Roy D8/27

(71) Applicant: **Matthew Orcutt**, Fort Wayne, IN (US)

* cited by examiner

(72) Inventor: **Matthew Orcutt**, Fort Wayne, IN (US)

Primary Examiner — Wan Laymon

(**) Term: **15 Years**

Assistant Examiner — Mark Booker

(21) Appl. No.: **29/563,109**

(74) *Attorney, Agent, or Firm* — Laurence T. Pearson

(22) Filed: **May 2, 2016**

CLAIM

(51) **LOC (10) Cl.** **24-01**

I claim the ornamental design for a dilutor claw for chromatographic equipment, as shown and described.

(52) **U.S. Cl.**

USPC **D24/232**

DESCRIPTION

U.S. PATENT DOCUMENTS

3,429,176 A * 2/1969 Topham G01N 30/30
73/23.25

D357,618 S * 4/1995 Macor D8/28

FIG. 1 is a perspective view of a dilutor claw for chromatographic equipment showing my new design.

FIG. 2 is a side view thereof;

FIG. 3 is a further side view thereof;

FIG. 4 is a front view thereof;

FIG. 5 is a rear view thereof;

FIG. 6 is a top view thereof; and,

FIG. 7 is a bottom view thereof.
